LUGGAGE CARRIER FOR A STATION WAGON BODY

Floyd A. Simon, 3365 White Beach Lane,
Youngstown, Ohio

Filed Apr. 23, 1964, Ser. No. 79,670

Term of patent 7 years

(Cl. D14—27)

FIG. 1

FIG. 2

FIG. 3

FIGURE 1 is a side elevation of a luggage carrier for a station wagon body, showing my new design.

FIGURE 2 is a front elevational view thereof.

FIGURE 3 is a rear elevational view thereof.

The top not shown is substantially plain.

The automobile fragmentarily shown in broken lines is included for illustrative purposes only.

I claim:

The ornamental design for a luggage carrier for a station wagon body, as shown and described.
